DESIGN FOR A RUFFLING OR COLLARETTE.

SPECIFICATION forming part of Design No. 14,129, dated July 21, 1883.
Application filed June 23, 1883. Term of patent 3½ years.

UNITED STATES PATENT OFFICE.

HERMAN ROSENTHAL, OF NEW YORK, N. Y.

DESIGN FOR A RUFFLING OR COLLARETTE.

SPECIFICATION forming part of Design No. 14,129, dated July 24, 1883.

Application filed June 23, 1883. Term of patent 3½ years.

To all whom it may concern:

Be it known that I, HERMAN ROSENTHAL, a citizen of the United States, residing at New York, in the county of New York and State of New York, have invented and produced a new and original Design for a Ruffling or Collarette, of which the following is a specification.

This design consists in a depending apron connected to the top edge of the ruffling or collarette by a rounded curve, so as to impart to the article a novel and ornamental appearance.

In the accompanying drawings, Figure 1 represents a face view. Fig. 2 is an end view.

Similar letters indicate corresponding parts.

In the drawings, the letter A designates the band to which the ruffling or collarette B is secured. The top edge of this ruffling or col-

larette is turned over in a graceful curve, a, so as to form a depending apron, b. By these means a novel and ornamental appearance is imparted to the article.

What I claim as new, and desire to secure by Letters Patent, is—

The design for a ruffling or collarette, consisting of the depending apron b, joined to the body of the article by a graceful curve, a, as shown and described.

In testimony whereof I have hereunto set my hand and seal in the presence of two subscribing witnesses.

HERMAN ROSENTHAL. [L. S.]

Witnesses:

W. HAUFF,
E. F. KASTENHUBER.
